UNITED STATES PATENT OFFICE.

ERNEST THOMAS KELL, OF BENTON, ILLINOIS.

COMBINED SHOVELING AND LOADING DEVICE.

Application filed June 5, 1922. Serial No. 566,096.

To all whom it may concern:

Be it known that I, ERNEST T. KELL, a citizen of the United States, and a resident of Benton, in the county of Franklin and State of Illinois, have invented a new and useful Improvement in Combined Shoveling and Loading Devices, of which the following is a full, clear, and exact description.

My invention relates to improvements in combined shoveling and loading devices, and it consists in the combinations, constructions, and arrangements herein described and claimed.

An object of my invention is to provide a combined shoveling and loading device which will convey the coal, which has already been dynamited, to a mine car or the like.

A further object of my invention is to provide a device of the character described which has novel means for loosening the dynamited coal.

A further object of my invention is to provide a device of the character described which is adapted to move toward the pile of coal as the coal is being carried away.

A further object of my invention is to provide a device of the character described which is mounted on caterpillar trucks, thereby providing a strong support to the device.

A further object of my invention is to provide a device of the character described which has a separate power unit for the conveying of the coal and for the moving of the device.

A further object of my invention is to provide a device of the character described which has a novel bucket scooping arrangement.

Other objects and advantages will appear in the following specification, and the novel features of the invention will be particularly pointed out in the appended claims.

My invention is illustrated in the accompanying drawings, forming part of this application, in which

Figure 1 is a plan view of the device,

Figure 2 is a side elevation of the device,

Figure 3 is a longitudinal section of a portion of the device,

Figure 4 is a perspective view of the bucket used, and

Figure 5 is a sectional view of the digging end of the device.

In carrying out my invention, I provide

a frame 1 on which is mounted a power source 2, and a second power source 3. The motor 2 is connected by a reversing mechanism 4 and a chain 4' with a caterpillar truck 5. From this construction it will be observed that the frame 1 may be moved forwardly or backwardly by merely actuating a lever 6 so as to operatively engage the motor 2 with the endless tread 5. The rear of the device is supported by wheels 7.

A bucket carrying means comprising roller chains 8 and buckets 9 is disposed in the front of the frame 1 (see Figures 1 and 3). The chains 8 are disposed around sprockets 9' and 10, and pivotally support the buckets 9 therebetween. The sprocket 10 is secured to a shaft 11 which in turn is driven by a belt connection 12 from the motor 3. As shown in Figure 1, the motor 3 is preferably of the electric type, although it may be of any other type desired. As heretofore stated, the buckets 9 are pivotally carried by the chains 8 by means of trunnions 13 which extend transversely from the buckets 9 at the vertices thereof. The buckets in reality form triangular-shaped conveyors. As clearly shown in Figure 4, the front edge of the bucket 9 is serrated as at 14 so as to more readily scoop up the coal which has already been blasted. The side 15 of the bucket has laterally extending ears 16 which are adapted to engage with the lugs 17, these lugs being parts of the chain 8.

Guide members 18 are carried by the frame 1 and support the buckets and chains during a portion of their trip. A second pair of guide members 19 are disposed between the sprockets 9' and 10 and are adapted to support the ears 16 after the buckets have been emptied. It will be noted from Figure 3 that the buckets moving toward the end of the frame 1 have their laterally extending projections 20 caught in grooves 21, whereby the front end of the bucket is kept down and forced into engagement with the pile of coal as the back portion is swung up and around the sprocket 9'. As soon as the sprocket 9' starts to carry the bucket 9 toward the guideways 18, the projections 20 have been pushed forwardly so as to clear the guideways 21, and the lugs 17 have engaged with the ears 16 of the bucket so as to lift the bucket into the position shown in Figure 3 of the drawings. The weight of the coal which was formerly carried by the

side 22 of the bucket is now carried by the side 15, this weight in turn being supported by the guideways 18. A further movement of the bucket carries it over the sprocket 10, the lugs 17 tipping the bucket so as to empty the coal therefrom onto a conveyor belt 23. A shield 24 prevents the coal from entering the compartment which contains the motors 2 and 3. It will also be apparent that the bucket which has just previously been dumped, forms a shield for the coal which is being dumped by the succeeding bucket, thereby preventing the coal from spilling over the end of the conveyor 23. The conveyor 23 carries the coal to any loading point, such as a coal car or a coal pile (not shown). The conveyor 23 forms no part of my invention, except in so far as it cooperates with the parts hereinbefore described.

The conveyor is actuated by any means, such as by a motor (not shown). The buckets in rounding the sprocket 10 have their ears 16 engaged by the guideways 19 so as to swing the bucket into the desired position. As the bucket moves on, the side 22 engages with the floor 24 of the frame 1, this floor being adapted to guide the projections 20 of the bucket into the guideways 21. In case the floor of the coal pile, which is being carried away by means of the bucket 9, is below the floor 24 of the frame 1, the end of the floor 24 may be lowered. This construction is clearly shown in Fig. 5 of the drawing.

A plate 25 is pivotally secured at 26 to the frame 1 and is adapted to form a contiguous wall with the floor 24. The frame 25 has upwardly extending lugs 27 through which bolts 28 are disposed, these bolts being slidably mounted in slots 29 in the sides 40 of the frame 1. It is obvious from this construction that the bolts 28 may be loosened so as to permit the plate 25 to drop into the dotted line position shown in Figure 5, whereupon the buckets 9 will scoop the coal 45 from a lower plane.

In case the coal which has been dynamited is not loose enough so as to readily fall into the buckets 9, means for breaking up the coal is actuated. In fact this means is preferably kept in operation during the operation 50 of the buckets 9. As clearly shown in Fig. 2, the shaft 30 which supports the sprockets 9' also supports sprockets 31. These sprockets are mounted on the inside of the frame 1 and adjacent to the walls of the frame. Sprockets 34 and 35 are carried by the sides 55 of the frame 1 and are substantially in vertical alinement with respect to each other. A roller chain 36 is mounted on the sprockets 31, 34, and 35, this roller chain carrying picks 37. The chains 36 are so disposed that the picks 37 will project beyond the end of the frame 1 when the picks are passing between the sprockets 34 and 35. As shown 60 in Figure 2, the picks 37 are removably se-

cured to the chains by means of set screws 38. If the coal is not filling the buckets 9 to the desired capacity, the frame 1 may be moved towards the pile of coal by means of the engine 2 and the caterpillar trucks 5 so as to cause the picks 37 to gouge into the pile of coal and to break up the pile into smaller pieces, whereupon the coal will readily fill the buckets and be carried away by the conveyor 23.

From the foregoing description of the various parts of the device, the operation thereof may be readily understood. As heretofore stated, when it is desired to remove a pile of coal which has previously been dynamited, the tractor is moved towards the desired pile by means of the motor 2. As soon as the tractor has reached the pile, the bucket conveying mechanism may be actuated, and the coal breaking mechanism also actuated, whereby the coal from the pile will be carried to the conveyor 23 and from thence to the desired location. The buckets 9 are held in a horizontal position while they are being filled and are also moved toward the pile of coal while they are being filled in the manner herebefore described. It is obvious that as fast as the buckets carry away the coal which is disposed adjacent to the forward end of the machine, the machine may be moved towards the pile, whereby the buckets will again carry away the coal deposited adjacent to the end of the machine.

The device consists of relatively few parts and is durable and efficient for the purpose intended.

I claim:

1. A device of the type described comprising a movable frame, an endless bucket conveyor disposed adjacent to one end of said frame and being adapted to convey a pile of loose material into said frame, said conveyor comprising chains, buckets pivotally carried by said chains, said buckets having laterally extending projections, guide members carried by said frame and being disposed so as to engage with the projections of said buckets during the digging operation of said buckets, whereby said buckets are held in the same plane during a part of their movement and means for moving the guide members with respect to the frame.

2. In a device of the character described, a pair of endless chains, triangular-shaped buckets pivotally carried by said chains, laterally extending projections carried by the sides of said buckets, lugs carried by said chains and adapted to engage with the projections on said buckets during a portion of the movement of said buckets, and guide members adapted to engage with certain of said projections during another portion of the movement of the buckets.

3. In a device of the type described, a frame, a plate pivotally secured to one end of said frame, buckets carried by said frame and being adapted to pass over said plate, 5 guides carried by said plate, projections carried by said buckets and adapted to enter said guides, and means for securing said plate after it has been swung into any position desired.
- 10 4. In a device of the type described, a frame, endless chains carried by said frame, angular-shaped buckets having their ver-
- tices pivotally secured to said chains, certain links of said chains having lugs, guides carried by said frame, and ears carried by 15 each end of each bucket, the ears of one end being adapted to abut the projections on said chains during one part of the movement of said buckets, and the ears of the other end being adapted to be received in 20 said guides during another part of the movement of said buckets.

ERNEST THOMAS KELL.
